UNITED STATES PATENT OFFICE.

BENJAMIN WOLHAUPTER, OF NEW ROCHELLE, NEW YORK.

RAIL-ANCHOR.

1,344,016.

Specification of Letters Patent. Patented June 22, 1920.

Application filed January 25, 1919. Serial No. 273,120.

To all whom it may concern:

Be it known that I, BENJAMIN WOLHAUPTER, a citizen of the United States, residing at New Rochelle, in the county of Westchester and State of New York, have invented certain new and useful Improvements in Rail-Anchors, of which the following is a specification.

This invention relates to an improvement 10 in that class of rail anchors having a clamping engagement with the rail base and coöperating with a tie or other fixed abutment to check creeping of the rail in a longitudinal direction.

15 A primary object of the invention is to provide a rail anchor of a very simple construction, and one which is also simple of application and removal, while at the same time possessing maximum efficiency in its 20 intended purpose of securely engaging the rail and effectually checking or preventing creeping thereof. In connection with these fundamental objects the invention also has in view a construction of rail anchor which 25 is inherently very strong and is of such a simple construction that it may be readily and economically manufactured by rolling or other processes.

While meeting all of the requirements 30 above indicated it is proposed, according to the present invention, to provide a rail anchor which may be clamped or locked upon the rail base with a powerful clamping pressure. In the attainment of that important 35 object the invention provides a structure which is intended to be so correlated with the flanges of the rail base as to obtain a firm binding engagement therewith at a plurality of points, preferably in alternate relation, whereby a maximum clamping, binding, or locking effect is obtained without danger of injuring or breaking either the rail flange or the anchor itself. At the same time a distinctive object in this connection is 40 to provide substantial and reliable means whereby the anchor may be so applied to the rail base that it may become clamped or interlocked therewith through a powerful leverage action which exerts a strong upward flexing pressure on the edge of the rail flange.

With these and other objects in view which will more readily appear as the details of the invention are explained, the invention consists in the novel construction,

arrangement and combination of parts hereinafter pointed out, illustrated and claimed.

The essential and distinctive feature of the invention involved in the leverage action which exerts an upward flexing pressure on 60 the edge of a rail flange is necessarily susceptible of embodiment in a large variety of modifications, but for the purposes of the present application a few examples are illustrated of the more practical and apparent 65 ways of carrying the invention into effect.

In the illustrations of the drawings:—

Figure 1 is an elevation of a rail anchor constructed in accordance with the present invention shown in its initial position, 70 preparatory to the application of the pressure means for rocking the anchor on its fulcrum located above the rail base.

Fig. 2 is a view of the construction shown in Fig. 1 after the pressure or tightening 75 means have been adjusted to secure the desired clamping effect.

Fig. 3 is a detail elevation of a portion of a rail, showing in end elevation the improved anchor in operative relation to the 80 rail flange, which has been flexed upwardly and the rail supporting tie acting as the abutment, the deflection shown being greatly exaggerated for illustrative purposes.

Figs. 4 and 5 are companion views of a 85 modification of the invention showing the anchor before and after being tightened onto the rail base.

Fig. 6 is a view of a modification, showing by full and dotted lines the position of the 90 anchor parts respectively before and after tightening.

Figs. 7, 8 and 9 are views of additional modifications also illustrating by full and dotted lines the position of the anchor parts 95 before and after tightening.

Like references designate corresponding parts throughout the several figures of the drawings.

All forms of the improved rail anchor 100 have the same simple structural characteristic, namely that of a single piece or bar of metal 1 formed at one end with a rail flange engaging jaw 2. The body of the anchor designated by the numeral 1 may simply 105 consist as shown in Figs. 1 and 2 of the drawings, of a substantially straight bar extended in a direction away from the jaw 2 into what may be termed a tail member 3 adapted to lie below the rail flange opposite 110

the flange which is engaged by the jaw 2. This jaw 2 is formed by a looped or doubled part of the bar adapted to receive and extend over one rail flange, and consists of the 5 upper and lower clamping jaw members 4 and 5 integrally connected at one end by the fold or bight 6, the said jaw members having a spaced relation to provide an ample rail flange clearance space 7. The two members 10 4 and 5 of the engaging jaw are spaced a sufficient distance apart to provide ample clearance for the flanges of various sized rails, and the upper member 4 is also preferably of sufficient length to provide a ful- 15 crum point a considerable distance inside the side edge of the rail flange, thereby adapting the anchor to rail bases of many different widths and of many different thicknesses of rail flange, thus making the 20 anchor practically susceptible of universal application to all standard sizes of rails. Furthermore, by reason of the jaw forma- 25 tion described the jaw of the anchor can be easily and readily slipped over the flange of the rail so as to bring the same into contact respectively with the upper side of the flange and the lower outer edge portion of the flange, thereby permitting of the lever- 30 age action which is contemplated by the present invention to provide for clamping the anchor tightly upon the rail base. Therefore, it will be observed that the rail flange engaging jaw 2 of the anchor includes, in addition to the structural fea- 35 tures already referred to, a fulcrum bearing 8 at the inner lower corner of the upper jaw member 4 which contacts with the top of the rail flange, and a pressure bearing face 9 formed at the upper side of the lower jaw 40 member 5 for engagement with the lower outer edge portion of the rail flange en- gaged by the jaw.

As above indicated, the tail or tail member 3 of the anchor body is extended from the jaw 2 beneath the flange of the rail opposite the flange engaged by the jaw, and one of the distinctive and practical features of the present invention resides in associating with the said tail member 3 adjustable pressure means. These means are intended to exert pressure or force against the tail or body of the anchor in a direction causing the anchor to become a lever turning on the fulcrum 8 and exerting an upward pressure 55 against the edge of the rail flange at the point 9. Various forms and kinds of pressure or force applying means may obviously be utilized in carrying out this phase of the invention. For instance, in the construction 60 illustrated in Figs. 1 and 2 of the drawings, a simple wedge 10 may be introduced between the underside of the rail base and the upper side of the tail member 3 of the anchor, a groove or wedge seat 11 being con- 65 veniently provided at the upper side of the

tail member for guiding and seating the wedges as desired. After placing the engaging jaw of the anchor over one rail flange with the tail member of the anchor extending beneath the edge of the rail flange, 70 as shown in Fig. 1 of the drawings, the simple act of driving "home" the pressure or force applying wedge 10 causes the anchor to rock on its fulcrum 8, thereby lifting the pressure bearing face 9 of the lower 75 jaw 5 against the lower outer edge portion of the rail flange with the result of exerting a powerful upward flexing pressure on the rail flange and producing such a relative distortion of the interengaging parts at this 80 point as to bring the anchor into firm clamping or locking engagement with the rail base. This desirable result may be fully appreciated from the illustration of Figs. 2 and 3 of the drawings. In the same 85 connection it will be noted that the leverage action referred to is rendered very effective by reason of the anchor, in effect, having a binding engagement with the rail base at three points of contact, in alternating rela- 90 tion, namely at the points 9, 8 and 12, the latter point of contact (12) being through the intermediary of the pressure or force applying wedge.

By way of illustrating other forms of 95 pressure or force applying means applicable to the present type of anchor there is shown in Figs. 4 and 5 of the drawings a modification wherein the tail 3 of the anchor is formed with an upstanding threaded terminal 13 upon which is adjustably mounted a nut 14 whose flat top face 15 is adapted to have a bearing engagement with the under side of the flange opposite the flange en- gaged by the jaw. The turning-up of this 105 nut, under pressure, against the under side of the rail base produces the combined lever- 110 age and clamping action in the anchor already described.

In the illustration of Fig. 6 there is shown 110 a pressure or force applying means consisting of a screw or bolt 16 adjustably mounted in a threaded opening 17 in the tail of the anchor and having its upper bearing end 18 flatly engaging against the underside of 115 the rail base. The turning of this screw or bolt 16, in either direction provides for the tightening or loosening of the rail anchor in the manner already described.

Again, as suggested in Fig. 7 of the draw- 120 ings the tail of the anchor body may be pro- vided with a straight threaded shank 19 set at an inclination to the lower member of the jaw and having mounted thereon a beveled bearing washer 20 and an adjusting nut 21 125 behind the washer. The beveled face of the washer rides against the flat underside of the rail base under the adjusting pressure of the nut 21 and on account of the inclination of the threaded shank 19 with reference to 130

the rail base, the leverage action described results from the inward adjustment of the washer 20. Or, as shown in Fig. 8 the threaded shank 19 of the tail may be left substantially or more nearly in line with the lower member of the jaw, and a washer 22 employed having a beveled face 23 adapted to ride inwardly and downwardly against the edge of the rail flange under the pressure of the adjusting nut 21. This construction also produces the leverage effect already described.

Fig. 9 of the drawings illustrates a modification wherein the upper jaw member 4 is produced by a circular looping of one end of the bar and the squared-off end 8^a of the upper-jaw member has a flat bearing engagement with the inclined upper face of the rail flange and also constitutes the fulcrum point for the anchor. In this modification the same form of pressure or force applying means are shown as illustrated in Figs. 4 and 5 of the drawings, but in addition to such means the modification of Fig. 9. illustrates the applicability of the improvements to an anchor body of resilient or springy material which will inherently contribute to the clamping or binding grip of the anchor upon the rail when the leverage force or pressure is exerted by the adjustment of the pressure or force applying means. Furthermore in the form of construction shown in Fig. 9 the fold or bight 6 of the jaw is of much greater length than in the forms of construction already described with the added advantage of permitting the springy or resilient effect of the metal to augment the clamping effect produced by the leverage action. While the drawings show an anchor made from rectangular or round bars throughout with the jaw portion bent to shape, still it can be constructed from rolled sections and then sheared.

From the foregoing it is thought that the construction, action and many advantages of the herein described rail anchor will be readily apparent without further description and it will be understood that various changes in the form, proportion and minor details of construction may be resorted to without departing from the spirit or sacrificing any of the advantages of the invention.

I claim:—

1. A rail anchor provided with rail flange engaging means, and means for adjusting the anchor to exert an upward pressure on the bottom edge portion of a rail flange.

2. A rail anchor consisting of a lever provided with rail flange engaging means, and means for adjusting the anchor as a lever to exert an upward pressure on the bottom edge portion of a rail flange.

3. A rail anchor consisting of a lever having a bearing face adapted to engage beneath the edge portion of a rail flange, and

means for moving the lever in a direction to exert upward pressure applying a flexing force on said flange.

4. A rail anchor consisting of a lever having a fulcrum adapted to engage the top 70 of a rail flange and a bearing for engaging the edge portion of the flange, and means for moving the lever on its fulcrum.

5. A rail anchor consisting of a lever having a fulcrum adapted to engage the top 75 of a rail flange and a bearing for engaging the edge portion of the flange, and means for moving the lever on its fulcrum in a direction to exert upward pressure on the edge of the rail flange.

6. A rail anchor consisting of a lever having a fulcrum adapted to engage the upper side of a rail flange, and a bearing face adapted to engage the lower outer edge portion of the same flange, and pressure or 85 force applying means engaging the lever.

7. A rail anchor consisting of a lever having a rail flange engaging jaw fulcruming on top of the flange, and pressure means engaging the lever.

8. A rail anchor consisting of a lever having a rail flange engaging jaw fulcruming on top of the flange, and pressure means engaging the lever and the rail base.

9. A rail anchor consisting of a lever having a rail flange engaging jaw fulcruming on top of the flange, and pressure means engaging the lever and beneath the flange opposite the flange engaged by the jaw.

10. A rail anchor consisting of a lever 100 having a tail member and a flange engaging jaw fulcruming on top of a rail flange, and pressure applying means engaging said tail member.

11. A rail anchor consisting of a lever 105 having a tail member and a flange engaging jaw fulcruming on top of a rail flange, and pressure applying means engaging said tail member and the rail base.

12. A rail anchor consisting of a lever 110 adapted to be fulcrumed on the rail base, and pressure applying means engaging said lever and the rail base for causing movement thereof in a direction to exert upward flexing pressure on the edge portion of a 115 rail flange.

13. A rail anchor consisting of a lever having a tail member and a flange embracing jaw, said jaw fulcruming on top of the rail base and having a bearing beneath the 120 edge of the rail flange, and pressure applying means coöperating with the tail member.

14. A rail anchor consisting of a lever adapted to be fulcrumed on top of one rail flange and to engage beneath the edge portion of the same flange, and a pressure applying device engaging said lever and the opposite rail flange, the points of engagement of the lever with the rail flange and said pressure applying device alternating.

15. A rail anchor comprising a body provided with a tail member and with a flange engaging jaw whose upper member is provided with a fulcrum bearing and whose lower member is provided with a pressure bearing face to engage the edge of the rail flange, and pressure applying means engaging the tail member of the anchor.
  16. A rail anchor comprising a body having a tail member extending beneath one rail flange and a jaw embracing the opposite rail flange and having engagement with
- the top of said flange and the lower edge portion thereof, and pressure applying means engaging the tail member and the rail base and adapted to apply a flexing force to said edge portion of the flange.
- In testimony whereof I hereunto affix my signature in the presence of two witnesses.

BENJAMIN WOLHAUPTER.
